INSULATED CAR WALL

Charles D. Bonsall, Pittsburgh, Pa., assignor, by
mesne assignments, to Standard Railway
Equipment Manufacturing Company, a corpo-
ration of Delaware

Application June 12, 1937, Serial No. 147,969

8 Claims. (Cl. 189—34)

The invention relates to a wall which is insulated to prevent or retard transfer of heat through it from one side to the other and is especially adaptable for use in a wall, roof, floor or door for a railway refrigerator car which is used to transport perishable commodities.

One of the objects of the invention is to provide a wall of spaced apart metallic sheets with stiffeners connecting such sheets so that the sheets will cooperate to form a very strong structure to resist stresses against either side of the wall and to provide an insulating wall by putting insulating material between the sheets, and as the insulating materials now in general use are combustible, another object of the invention is to provide stiffeners of such construction that the sheets may be welded to them without igniting the insulating material.

A still further object is to provide means to insulate the stiffeners so that heat will not be conducted by them through the wall.

Another object is to associate and arrange such insulating means so that it cooperates with the elements forming the stiffeners to provide hollow spaces to prevent the heat of welding from igniting the insulating material between the metallic sheets, and a further object is to insulate that portion of the wall occupied by the hollow spaces by filling such spaces with non-combustible insulating material.

Another object is to provide a waterproof structure by connecting the associated parts of the wall together so as to prevent moisture from contacting the insulating material and reducing its insulating efficiency.

Another object is to provide a metallic sheet wall having a smooth interior or exterior surface (or both if desired) made out of flat metallic sheets.

40. In the drawing:

Fig. 1 shows a typical application of my improved wall used as the floor of a railway refrigerator car.

Fig. 2 shows an enlarged cross section of the metallic sheets and stiffener shown in Fig. 1.

Figs. 3-8 inclusive show modified forms of stiffeners which may be used between the metallic sheet to accomplish the objects of the invention.

The drawing shows the usual parts of the car, such as side sill 1; side wall sheathing 2; side wall lining 3; side wall insulation 4 and side wall framing 5.

The form of my wall or floor shown in Figs. 1 and 2 comprises an upper metallic sheet 7 and lower metallic sheets 8 spaced therefrom and sub-

REISSUED

stantially parallel thereto, insulating material 9 between said sheets and an insulated stiffener 10 connecting the sheets. The stiffener comprises two metallic members, each of said members comprising an outer flange 13, an inner flange 14 and a web 15 connecting the flanges. The insulating fabric or other insulating material 16 is positioned between the inner flanges 14 of the two members and is preferably secured thereto by the rivet 17. The insulating fabric is bent to form flanges 18 and 21, which flanges cooperate with the webs 15 of the members to provide hollow spaces 22 and 23. The metallic sheets 7 and 8 are welded (24) to the outer flanges 13—13 and the spaces 23—23 prevent the heat of the welding from igniting the insulating material. When two upper sheets 7—7 (or two lower sheets 8—8) are used they may be joined by the welding material 24 which secures both of said sheets to the outer flange 13 of the member.

The insulating fabric 16 is made of some porous material which may be moulded in any desired shape, usually when wet, but which has sufficient stiffness, when dry, to maintain its form.

If desired, the spaces 22 and 23 may be filled with some non-combustible material, such as asbestos.

In the modification shown in Fig. 3 a fabric 30 is made of one flat piece of material extending between the upper 7 and lower 8 metallic sheets and the members 31—32 are secured on opposite sides of the fabric by the rivet 33. Each member is provided with an inner flange 34, an outer flange 35 and a web 36 to form the space 37. The metallic sheets 7—8 are welded (37) to the outer flange 35.

In the modification shown in Fig. 4 the fabric 40 is one flat piece of material extending diagonally between the upper 7 and lower 8 metallic sheets. The metallic members are positioned on opposite sides of the fabric and secured thereto and to each other by the rivet 41 and each member is provided with a web 42 and flange 43 to cooperate with the fabric to form the spaces 44 and 45. The upper and lower sheets are welded (47) to the flanges 43.

Fig. 4 is an improvement over Fig. 3 because the welds are in line with each other.

Fig. 5 is a modification of the construction shown in Fig. 4 wherein the members are provided with lips 50 which overlap the fabric to hold it in place.

Fig. 6 shows a modification wherein a short piece of fabric 60 is positioned between the two metallic members 61—62 to provide an insula-

tion therebetween and other pieces of fabric 63 are positioned on opposite sides of the stiffener which extend between and preferably contact both the upper 7 and lower 8 metallic sheets. 5 The metallic members are formed so as to cooperate with one of the pieces of fabric to form the spaces 64 and 65.

Fig. 7 shows a modification wherein two channel shape pieces 70 of fabric are positioned between the upper 71 and lower 72 metallic members and preferably secured thereto by the rivet 73. These U-shape pieces of fabric 70 form a space 74 on each side of each member. 10

Fig. 8 shows a modification wherein a stiffener 15 is used in a wall wherein the metallic sheets 7-8 are spaced relatively far apart, in which case it may not be necessary for the fabric 71 to extend all the way between the two metallic sheets, so I provide an intermediate metallic member 72 between the upper 73 and lower 74 metallic members and the fabric 71 is formed so that it cooperates with a part of the metallic member to provide the space 75. 20

In all of the above described structures each 25 of the metallic members is provided with a flat part to which the adjacent metallic sheet is welded and fabric is positioned between the two (or more) metallic members so that there is no direct conduit for heat from one side of the wall 30 to the other; furthermore, each structure shows the fabric formed to cooperate with a part of one of the metallic members to provide a space so that the heat of welding will not ignite the combustible insulation between the metallic sheets. 35 In some of the above described constructions the metallic members and the fabric are associated so that they will transmit a direct load from one metallic sheet to the other either in tension or compression, therefore, the stiffeners cause the 40 metallic sheets to become compression and tension members of a beam to resist stresses imposed on the wall from one side or the other thereof.

The accompanying drawing illustrates the preferred form of the invention, though it is to be understood that the invention is not limited to the exact details of construction shown and described, as it is obvious that various modifications thereof, within the scope of the claims, will occur to persons skilled in the art. 45

I claim:

50 1. An insulating wall comprising spaced apart metallic sheets, combustible insulating material between said sheets and an insulated stiffener connecting said sheets, said stiffener comprising a metallic member welded to each sheet and an insulating fabric between said members, said fabric and said members being associated and arranged to provide hollow channels to prevent the heat of welding from igniting said combustible insulation.

55 2. An insulating wall comprising spaced apart metallic sheets, combustible insulating material between said sheets and an insulated stiffener connecting said sheets, said stiffener comprising a metallic member welded to each sheet and an insulating fabric between said members and secured thereto, said fabric and said members being associated and arranged to provide hollow channels to prevent the heat of welding from igniting said combustible insulation. 60

65 3. An insulating wall comprising spaced apart metallic sheets, combustible insulating material

between said sheets and an insulated stiffener connecting said sheets, said stiffener comprising two channel shaped metallic members each having one flange thereof welded to one of said sheets, and an insulating fabric between the other flanges of said members, said insulating fabric having portions which cooperate with the webs of said members to provide hollow spaces to prevent the heat of welding from igniting the combustible insulation. 5

4. An insulating wall comprising spaced apart metallic sheets, combustible insulating material between said sheets and an insulated stiffener connecting said sheets, said stiffener comprising two channel shaped metallic members each having one flange thereof welded to one of said sheets, and an insulating fabric between the other flanges of said members, said insulating fabric having portions which cooperate with the webs of said members to provide hollow spaces to prevent the heat of welding from igniting the combustible insulation, and means to secure the last mentioned flanges and the fabric together. 10

5. An insulating wall comprising spaced apart metallic sheets, combustible insulating material between said sheets and an insulated stiffener connecting said sheets, said stiffener comprising a metallic member welded to each sheet and an insulating fabric between said members, said fabric and said members being associated and arranged to provide hollow channels to prevent the heat of welding from igniting said combustible insulation and non-combustible insulation in said hollow channels. 25

6. An insulating wall comprising spaced apart metallic sheets, combustible insulating material between said sheets and an insulated stiffener connecting said sheets, said stiffener comprising a metallic member welded to each sheet, and an insulating fabric between said members, said fabric and said members being associated and arranged to provide a hollow space on each side of said members to prevent the heat of welding from igniting said combustible insulation. 30

7. An insulating wall comprising spaced apart metallic sheets, combustible insulating material between said sheets, and an insulated stiffener connecting said sheets, said stiffener comprising a piece of stiff insulating fabric extending between said sheets, a metallic member on each side of said fabric, and means to secure both of said members to said fabric, each of said members having a flat part to which the adjacent metallic sheet is welded and a portion which cooperates with the fabric to provide hollow spaces to prevent the heat of welding from igniting the insulation. 45

8. An insulating wall comprising spaced apart metallic sheets, combustible insulating material between said sheets, and an insulated stiffener connecting said sheets, said stiffener comprising a piece of stiff insulating fabric extending between said sheets, a metallic member on each side of said fabric, and means to secure both of said members to said fabric, each of said members having a flat part to which the adjacent metallic sheet is welded and a portion which cooperates with the fabric to provide hollow spaces to prevent the heat of welding from igniting the insulation, each of said members provided with a lip 55 to hold the fabric in place. 60
